UNITED STATES PATENT OFFICE.

BERTRAM ALBERT LEVY, OF NEW YORK, N. Y.

METHOD OF PROJECTING PICTURES.

No. 829,276.

Specification of Letters Patent.

Patented Aug. 21, 1906.

Application filed September 2, 1905. Serial No. 276,860.

To all whom it may concern:

Be it known that I, BERTRAM ALBERT LEVY, a citizen of Melbourne, Australia, and a resident of the United States, residing at 5 New York, in the county of New York and State of New York, have invented certain new and useful Improvements in Methods of Projecting Pictures; and I do hereby declare the following to be a full, clear, and exact description of the invention, such as will enable others skilled in the art to which it appertains to make and use the same.

My invention relates to improvements in methods of projecting pictures; and the object of my invention is to show upon a screen a slowly-growing picture, which grows as the artist sketches it in lines of white or colored light upon a dark background.

My invention will be understood by reference to the accompanying drawings, in which—

Figure 1 shows the simplest form of the apparatus. Fig. 2 is a front view of the screen, showing the picture as it appears thereon; and Fig. 3 shows an improved form of the apparatus with a picture projected on the screen.

Referring first to Figs. 1 and 2, *a* represents a screen of any suitable material, as 30 white cotton fabric, for instance. *b* represents a magic lantern. *c* represents a slide-support for the magic lantern, leaving the lens of said lantern entirely unobstructed, and *d* represents a slide having its front face 35 covered with a black or other opaque coating, which can be removed by any suitable means, such as a pencil, brush, or stylus. The apparatus is of course to be used in a perfectly dark room and is so arranged that 40 the screen appears perfectly black or of any other desired color when the glass slide *d* is in the front of the magic lantern. The artist then takes a pen, pencil, or brush and draws a picture upon the slide *d* by removing the 45 coating in certain places. The result is that a picture appears on the screen greatly enlarged in lines of white or colored light upon a dark background. The artist of course varies the picture as he pleases. It may represent persons, events, or may illustrate a 50 story which the artist tells as he sketches. The apparatus is so arranged that the screen is absolutely unobstructed, and nothing appears thereon but the slowly-growing picture, except that in some cases the shadow of 55 the pencil is seen. This does not destroy the

illusory effect, but rather heightens it if anything.

In the form of device shown in Fig. 3, 1 represents a lantern of any desired construction, 6c but preferably containing a strong electric light having a lens 2. 3 represents a plate-mirror arranged at an angle to the lens, so as to throw the lines of light upwardly through another lens 4. 5 represents a slide, preferably of glass, which is provided with an opaque coating on its upper surface, which coating may be readily removed by a pen, brush, or stylus. It should be noted that the space above the slide 5 is perfectly unobstructed, so that the artist can sit on a chair in front of the table 9 on which the apparatus rests and can sketch freely upon the slide 5, moving his body and arms into any position he may wish. The rays of light which pass 75 through the slide 5 after a portion of the coating has been removed are received upon a lens 6, which directs them upon a concave mirror 7, which throws an enlarged image on the screen 8. The lens 6 is carried by the 80 hanger 10 on the rod 11 and may be moved up or down to vary the size of the image, and the mirror 7 is also pivotally mounted on the hanger 12, fastened to the rod 11, and is arranged to swing in the arc of a circle, so as to 85 throw the image up or down on the face of the screen, as may be desired, or to cut it off entirely from the screen.

With this apparatus the artist by drawing a picture upon the slide 5 will cause said picture to be reproduced greatly enlarged upon the screen in lines of white or colored light on a dark background, and the audience sitting in the dark will not be able to see how it is produced, the result being very striking. 95 The greatest freedom of movement is provided for the artist, and, in fact, it may be said that with this apparatus the services of an artist and not a mere copyist are necessary, the result being that any sort of a picture may be produced, not only a line picture but pictures with brush effects and thoroughly perfect in technique or color effects. The magic lantern may be placed either in front of or behind the screen, which in the 105 latter case must be made of thin translucent material.

Having thus described my invention, what I claim as new, and desire to secure by Letters Patent of the United States, is—

1. The method of projecting pictures, which consists in sketching a picture upon a

2
transparent medium covered with a light-excluding coating by means of an instrument which can be so manipulated as to produce either pen or brush effects, and thereby 5 partly removing said coating, allowing a light to strike upon said medium, and holding the instrument in such a position as to allow the light to pass freely at all times through the transparent medium upon a screen, 10 whereby as said coating is removed a slowly-growing picture appears upon the screen, substantially as described.

2. The method of projecting pictures, which consists in sketching a picture free-hand upon a transparent medium provided 15 with a light-excluding coating by means of an instrument which can be so manipulated

as to produce either pen or brush effects, and thereby removing said coating in certain places, projecting diverging rays of light 20 upon said medium, receiving said rays as they pass through said medium upon a screen, and holding the instrument in such a position as to allow the light to pass freely at all times through the transparent medium upon said 25 screen, whereby a slowly-growing picture appears upon the screen as the artist sketches, substantially as described.

In testimony whereof I affix my signature in presence of two witnesses.

BERTRAM ALBERT LEVY.
